Albert E. Tepfer
Inventor

By his Attorney *Almonia*

UNITED STATES PATENT OFFICE.

ALBERT E. TEPFER, OF NEW YORK, N. Y.

DESIGN FOR A BANDING FOR LIGHTING-FIXTURES.

48,953.

Specification for Design.

Patented Apr. 25, 1916.

Application filed December 15, 1915. Serial No. 67,068. Term of patent 7 years.

To all whom it may concern:

Be it known that I, ALBERT E. TEPFER, a citizen of the United States, residing at New York city, in the county and State of New York, have invented a new, original, and ornamental Design for a Banding for Lighting-Fixtures, of which the following is a specification, reference being had to the accompanying drawing, forming part thereof.

The figure is a fragmentary plan view of a banding showing my new design.

I claim:—

The ornamental design for a banding for lighting fixtures, as shown.

ALBERT E. TEPFER.

Witnesses:

CLARICE FRANCK,
JUDITH PARDEE.
